PRIMER FOR INTERNAL COMBUSTION MOTORS

Jesse L. Osburn and William H. Fain,
Houston, Tex.

Application November 22, 1940, Serial No. 366,600

4 Claims. (Cl. 123—180)

This invention relates to a primer for an internal combustion motor.

An object of the invention is to provide an automatic primer for supplying a priming charge of motive fluid to the motor upon starting the motor when it is cold and for then automatically cutting off the priming fluid when the motor has reached a predetermined temperature or when the vacuum in the intake manifold has reached a predetermined intensity.

By the use of the primer herein described, the choke valve and shaft or cables or the electrically operated choke, commonly used, may be dispensed with. Choke devices above referred to and commonly employed are under the control of the operator and in use are often inadvertently allowed to remain partly closed thus causing the motor to be supplied with a mixture which is too rich or causes flooding of the motor. The invention herein described is effective to automatically supply to the motor the necessary motive fluid for priming purposes but positively preventing the supply of additional priming fluid after the necessity therefor has ceased.

It is another object of the invention to provide an automatic priming device which conduces to the quick and easy starting of the motor thereby reducing wear on the starter and drain of the battery to a minimum and eliminating backfiring or misfiring of the motor together with the attendant shocks to the driving gearing of the vehicle.

It is a further feature of the invention to provide a very simple type of primer that may be cheaply produced and readily installed.

With the above and other objects in view the invention has particular relation to certain novel features of construction, operation and arrangement of parts, an example of which is given in this specification and illustrated in the accompanying drawing, wherein:

Figure 1 shows a sectional view of the primer shown in closed position, and

Figure 2 shows a side view of the carburetor and intake pipe showing the primer mounted in relation to the intake and exhaust manifolds.

Referring now more particularly to the drawing wherein like numerals of reference designate the same parts in each of the figures the numeral 1 designates the body which is preferably in the form of a cylindrical block and screwed onto the ends of which are the caps 2 and 3. Clamped between the cap 2 and the adjacent end of the body there is a flexible diaphragm 4 and clamped between the cap 3 and the adjacent end of the

body there is a flexible diaphragm 5. The primer may be secured to the exhaust manifold 6 of the motor by means of a suitable bracket 7, made integral with cap 2, or may be separately constructed. Fastened to this bracket there is a thermostat 8 preferably U-shaped in form and one end of which may be secured to the bracket by the bolt 9. The free end of the thermostat is arranged opposite the corresponding end of the plunger 10 which works through a bearing in the cap 2 and whose inner end is formed with a head 11 having an oval bearing face which rests against the center of the diaphragm 4. When the thermostat 8 is cold, its free end will be relieved from the plunger 10, but when it reaches a predetermined temperature its free end will act against the plunger 10 which in turn will operate against the diaphragm 4. The influence of the thermostat on the plunger 10 may be regulated by an adjusting screw 12 which is threaded through the bracket 7, and whose inner end bears against the arm of the thermostat which is attached to said bracket.

The cap 3 has a deep socket 13 in which is located a strong coil spring 14 which is seated on an adjustable disc 15. This disc has a swiveling connection with an adjusting screw 16 which is threaded through the cap 3 and the other end of the spring 14 bears against the outer side 30 of the diaphragm 5.

The body 1 has a central opening 17 extending entirely therethrough one end of which is enlarged forming a chamber 18.

A hollow tubular valve casing 19 is screwed into the opening 17, said casing having an enlarged head 20 with a gasket 21 clamped between said head and the bottom of the chamber 18. A valve stem 22 is fitted into the valve casing and has a longitudinal flute 23 extending from end to end thereof. The inner end of the valve stem 22 is reduced in diameter and formed into a tapered valve 24 adapted to open and close the annular seat 25 in the corresponding end of the valve casing.

An actuating rod 26 has one end seated on the diaphragm 5 and the other end of this rod is seated in a deep socket in the opposing end of the valve stem 22.

In Figure 1 the parts are shown in the position they will occupy when the motor is running and the thermostat 8 is subjected to the normal heat of the motor. Under these conditions the valve 24 will be held seated against the seat 25 to positively close the latter, the rod operating

against the diaphragm 5 to place the spring 14 under the required compression.

The primer is connected into a branch line 27 which leads from the fuel pipe 28. This fuel pipe 28 leads from the fuel pump and enters the carburetor 29 which is connected to the intake pipe 30 leading to the intake manifold 31 of the motor. The intake pipe 30 is controlled by means of the conventional type of throttle valve 32. The branch line 27 leads from the fuel pipe 28 and enters one side of the body 1 and leading from it there is a duct 33 which conducts a priming fluid from the branch line 27 and which fluid passes through the seat 25, when the valve 24 is open, and passes thence along the flute 23 into the chamber 18 and passes thence through the duct 34, leading from said chamber, and through the pipe 35 into the intake pipe 30. The pipe 35 terminates in a restricted choke 36 so that the priming fluid will be projected, under fuel pump pressure, into the intake pipe in a small stream which will be carried along with the air to the motor combustion chambers. It is to be noted that when the motor is cold, the free end of the thermostat will be relieved from the plunger 10 and the spring 14 will hold the valve 24 open as hereinabove explained so that the priming fluid can readily flow from the fluid pipe 28 through the branch line 27 and through the primer into the intake pipe 30 when the starter is operated to start the motor. The priming operation will continue so long as the throttle valve 32 is maintained partly open until the thermostat 3 has reached a temperature to cause it to act against the plunger 10 to close the valve 24. It is to be here noted that the end of the stem 22 opposite the valve 28 is at all times in abutting relation with the diaphragm 4 and said diaphragm and stem move in unison.

There is a suction pipe 37 one end of which is extended through the cap 3 on the opposite side of the diaphragm 5 from the valve seat 25 and the other end of which terminates in the intake pipe 30.

The intensity of the vacuum in the intake pipe varies with the position of the throttle valve 32, the vacuum being highest when the throttle valve is closed and the engine is idling, the vacuum decreasing as the throttle valve is opened. The compression of the spring 14 is so adjusted, by the adjusting screw 16, that the diaphragm 5 will be pulled away from the rod 26 only when the motor is idling and the vacuum is highest in the intake pipe 30 and simultaneously the diaphragm 4 will operate against the valve stem 22 to close the valve 24. Therefore, if at any time before the thermostat 3 has reached its predetermined temperature and has closed the valve 24, the throttle valve 32 should be closed, the valve 24 will also be closed, by the action of the diaphragm 4 thus preventing an excess of motive fluid from reaching the motor.

When the motor is running but still cold the valve 24 will be controlled by the suction of the motor. Under increase of motor speed the throttle valve will have been opened wider and the vacuum in the intake pipe 30 decreased allowing the spring 14 to act to open the valve 24 further

to admit more priming fluid; but upon closing of the throttle valve the speed of the motor will decrease and the vacuum in the intake pipe 30 will increase thus relieving the diaphragm 5 from the rod 26 and allowing the diaphragm 4 to move the valve 24 toward closed position to decrease the supply of priming fluid; however when the motor is hot and the thermostat 3 is in action said thermostat takes control and maintains the valve 24 in closed position until the motor again cools.

The drawing and description are illustrative merely while the broad principle of the invention will be defined by the appended claims.

What we claim is:

- 15 1. A primer for an internal combustion motor, comprising a body having a conduit leading therethrough connected at one end to a source of motive fluid supply, and at its other end into the motor intake, a valve movable to open or close the conduit and to thereby control the flow of fluid therethrough, yieldable means which include diaphragms arranged on opposite sides of the valve for normally holding the valve in open position, and means when under the influence of the heat of the motor effective to move the valve to closed position to close the conduit.
- 20 2. A primer for an internal combustion motor, comprising a body having a conduit leading therethrough, connected at one end to a source of motive fluid supply, and at its other end into the motor intake, a valve movable to open or close the conduit and to thereby control the flow of fluid therethrough, yieldable means which include diaphragms arranged on opposite sides of the valve for normally holding the valve in open position, and a suction conduit connected into the motor intake through which suction may be applied to the valve holding means to effect closing of the valve.
- 25 3. A primer for an internal combustion motor comprising a body having a closed conduit for liquid under pressure leading therethrough, connected at one end to a source of motive fluid supply, and terminating at its other end in a restricted discharge nozzle in the motor intake, a valve movable to open or close the conduit and to thereby control the flow of fluid therethrough, a suction conduit connected into the motor intake and also connected into said body and a diaphragm across the body separating said conduits and arranged to be effected by the suction of the motor to allow the closing of the valve.
- 30 4. A primer for an internal combustion motor comprising a body having a conduit adapted to conduct liquid under pressure therethrough and connected at one end to a source of motive fluid supply and at its other end into the motor intake, a valve movable to open or close the conduit and to thereby control the flow of liquid therethrough, movable means on opposite sides of the valve and including a flexible diaphragm for normally holding the valve in open position, and means when under the influence of the heat of the motor effective to co-act with said movable means to move the valve to closed position to close the conduit.
- 35 5. A primer for an internal combustion motor comprising a body having a conduit adapted to conduct liquid under pressure therethrough and connected at one end to a source of motive fluid supply and at its other end into the motor intake, a valve movable to open or close the conduit and to thereby control the flow of liquid therethrough, movable means on opposite sides of the valve and including a flexible diaphragm for normally holding the valve in open position, and means when under the influence of the heat of the motor effective to co-act with said movable means to move the valve to closed position to close the conduit.
- 40 6. A primer for an internal combustion motor comprising a body having a closed conduit for liquid under pressure leading therethrough, connected at one end to a source of motive fluid supply, and terminating at its other end in a restricted discharge nozzle in the motor intake, a valve movable to open or close the conduit and to thereby control the flow of fluid therethrough, a suction conduit connected into the motor intake and also connected into said body and a diaphragm across the body separating said conduits and arranged to be effected by the suction of the motor to allow the closing of the valve.
- 45 7. A primer for an internal combustion motor comprising a body having a conduit adapted to conduct liquid under pressure therethrough and connected at one end to a source of motive fluid supply and at its other end into the motor intake, a valve movable to open or close the conduit and to thereby control the flow of liquid therethrough, movable means on opposite sides of the valve and including a flexible diaphragm for normally holding the valve in open position, and means when under the influence of the heat of the motor effective to co-act with said movable means to move the valve to closed position to close the conduit.
- 50 8. A primer for an internal combustion motor comprising a body having a conduit adapted to conduct liquid under pressure therethrough and connected at one end to a source of motive fluid supply and at its other end into the motor intake, a valve movable to open or close the conduit and to thereby control the flow of liquid therethrough, movable means on opposite sides of the valve and including a flexible diaphragm for normally holding the valve in open position, and means when under the influence of the heat of the motor effective to co-act with said movable means to move the valve to closed position to close the conduit.
- 55 9. A primer for an internal combustion motor comprising a body having a conduit adapted to conduct liquid under pressure therethrough and connected at one end to a source of motive fluid supply and at its other end into the motor intake, a valve movable to open or close the conduit and to thereby control the flow of liquid therethrough, movable means on opposite sides of the valve and including a flexible diaphragm for normally holding the valve in open position, and means when under the influence of the heat of the motor effective to co-act with said movable means to move the valve to closed position to close the conduit.
- 60 10. A primer for an internal combustion motor comprising a body having a conduit adapted to conduct liquid under pressure therethrough and connected at one end to a source of motive fluid supply and at its other end into the motor intake, a valve movable to open or close the conduit and to thereby control the flow of liquid therethrough, movable means on opposite sides of the valve and including a flexible diaphragm for normally holding the valve in open position, and means when under the influence of the heat of the motor effective to co-act with said movable means to move the valve to closed position to close the conduit.
- 65 11. A primer for an internal combustion motor comprising a body having a conduit adapted to conduct liquid under pressure therethrough and connected at one end to a source of motive fluid supply and at its other end into the motor intake, a valve movable to open or close the conduit and to thereby control the flow of liquid therethrough, movable means on opposite sides of the valve and including a flexible diaphragm for normally holding the valve in open position, and means when under the influence of the heat of the motor effective to co-act with said movable means to move the valve to closed position to close the conduit.
